CIGARETTE MAKING MACHINE

Walter Everett Molins and Félix Frédéric Ruau,
Deptford, London, EnglandApplication June 1, 1933, Serial No. 673,889
In Great Britain June 10, 1932

6 Claims. (Cl. 131—39)

This invention relates to cigarette making machines, and refers more particularly to the tobacco feeding apparatus of such machines.

It has for its object to provide means whereby the escape of short tobacco from the tobacco mass during the feeding is prevented, with a view to simplifying the construction of the machine and improving the efficiency thereof, for as is well known, it has been the common practice to provide apparatus on cigarette making machines to gather short tobacco as it falls from the feeding mechanism and to re-feed it at some other point in the machine by special conveying and feeding devices. It is, of course, imperative that the short tobacco shall not be wasted in view of the high price of tobacco.

Apparatus for feeding tobacco usually comprises a hopper or container into which a mass of tobacco is placed and having at its base a feeding element which feeds the tobacco from the hopper to carded combing elements, usually rollers, which prepare it for use in the machine, and according to the present invention means are provided for sealing the hopper at the point below the gap or junction between the feeding means, and the combing means to prevent the escape of the short tobacco at this point. Further, the invention consists of a tobacco feeding device wherein movable feeding spikes or pins are provided for feeding the tobacco towards the combing element and arranged to grip the tobacco during the time they are moving towards the combing element.

Several ways of carrying the invention into effect will be described with reference to the accompanying drawings, in which:—

Figure 1 is a section of a tobacco feeding apparatus with the invention applied thereto.

Figure 2 is an enlarged view of the feed roller shown in Figure 1.

Figure 3 is a section on the line A B.

Figures 4 and 5 are diagrams illustrating the working of the apparatus, and

Figures 6 and 7 show modified forms of the invention.

Referring to Figures 1 to 5 which show a well known type of tobacco feeding apparatus, the tobacco is placed in the hopper 1 and fed upwardly by a feed element consisting of a roller 2 to a carded combing element in the form of a roller 3 which carries it beneath a brushing roller 4 which brushes back any surplus tobacco on the surface of the combing roller.

The tobacco is picked from the surface of the combing roller 3 by a picker roller 4a and show-

ered on to a distributor 5, in the present case a carded roller, from which it is again removed by a picker roller 6 and delivered to the filling trough 7 of the cigarette machine.

A shield 8 is provided beneath the combing roller 3, and concentric therewith, and collects any short tobacco which falls from the combing roller. Such short tobacco will collect in the portion of the shield nearest to the hopper, and will eventually be carried upwards by the carding of the combing roller.

The shield touches the surface of the smooth roller 2 at the base of the hopper, and seals the hopper at this point. The shield, therefore, scrapes the roller 2 clean and prevents any short tobacco or dust from falling out of the hopper.

The smooth roller 2 is made hollow as shown in Figure 3, and is provided with a number of sets of spikes or pins 9, each set being carried on a bar 10. These bars 10 are parallel to the axis of the roller, and are supported at their ends in bearings 11 in the roller flanges 12.

The bars 10 carry the pins 9 by means of short supporting levers 13 fixed to the bars, and the latter are also provided with cam levers 14 having rollers 15 thereon which engage with a fixed cam 16 as the roller rotates. The levers 13 and 14 form bell-cranks with the bars 10, as fulcrums.

As shown in Figure 3, the cam 16 is fixed to one of the shaft bearings 17 which is in turn fixed into the frame of the machine.

As the roller 2 rotates each set of pins in turn commences to protrude from the surface of the roller as the portion of the roller at which the particular set is located enters the hopper beneath the tobacco; see Figures 4 and 5. The pins 9, therefore, feed the tobacco round towards the combing roller 3 and just as the pins are approaching the surface of the said roller they are withdrawn into the interior of the roller owing to the change in shape of the cam.

Therefore, the surface of the roller 2 as it passes the scraper formed on the edge of the shield is quite even and no short tobacco can escape from the space between the rollers. As shown, three sets of pins are provided on the roller, but this number may be varied to suit requirements.

In the modification shown in Figure 6, a smooth roller 18 is fitted to form the bottom of the hopper, and the tobacco is fed by an oscillating sector, having carding on its surface.

The pins on the carding slant towards the

combing roller 3 so that on the forward movement tobacco is fed to the comber and on the rearward movement the pins slip beneath the tobacco without disturbing it. A shield 8 is fitted as before.

Referring to Figure 7, the smooth roller is dispensed with and a plate 20 sloping towards the combing roller and forming a combination of the shields 8 may be used through which a reciprocating carded feeder plate 21 protrudes and feeds the tobacco as described in the case of Figure 6. In this case, the shield 8 is replaced by an extension of the plate 20 formed concentric with the surface of the combing roller.

It will be seen that by constructing the feeding devices according to this invention that the shorts are regularly carried away with the remainder of the tobacco as no opportunity is afforded for the shorts to separate from the remainder.

What we claim as our invention and desire to secure by Letters Patent is:—

1. In a tobacco feeding apparatus the combination with a combing element, of a distributor element disposed to receive tobacco from the combing element, a feeding element to feed tobacco from a hopper to the combing element, said feeding element comprising a roller having retractable feeding spikes.

2. In a tobacco feeding apparatus the combination with a combing element, of a distributor element disposed to receive tobacco from the combing element, a feeding element to feed tobacco from a hopper to the combing element, said feeding element comprising a roller having retractable feeding spikes, and means for operating said spikes to cause the same to protrude from the roller during their passage through a hopper to feed tobacco to the combing element and to withdraw into the roller when they are not passing through the hopper.

3. In a tobacco feeding apparatus the combination with a combing element, of a distributor element disposed to receive tobacco from the combing element, a feeding element to feed tobacco from a hopper to the combing element, said feeding element comprising a roller having retractable feeding spikes pivotally mounted within the roller and a cam to operate said

spikes to cause them to protrude from or be withdrawn into the feeding roller.

4. In a tobacco feeding apparatus the combination with a combing element, of a distributor element disposed to receive tobacco from the combing element, a feeding element to feed tobacco from a hopper to the combing element, said feeding element comprising a roller having retractable feeding spikes and a shield disposed beneath the combing element and extending from the distributor element to the feeding element to prevent the escape of short tobacco from between the combing element and the distributor and feeding elements.

5. In a tobacco feeding apparatus the combination with a combing element, of a distributor element disposed to receive tobacco from the combing element, a feeding element to feed tobacco from a hopper to the combing element, said feeding element comprising a roller having retractable feeding spikes, means for operating said spikes to cause the same to protrude from the roller during their passage through the hopper to feed tobacco to the combing element and to withdraw into the roller when they are not passing through the hopper, and a shield disposed beneath the combing element and extending from the distributor element to the feeding element to prevent the escape of short tobacco from between the combing element and the distributor and feeding elements.

6. In a tobacco feeding apparatus the combination with a combing element, of a distributor element disposed to receive tobacco from the combing element, a feeding element to feed tobacco from a hopper to the combing element, said feeding element comprising a roller having retractable feeding spikes pivotally mounted within the roller and a cam to operate said spikes to cause them to protrude from or be withdrawn into the feeding roller, and a shield disposed beneath the combing element and extending from the distributor element to the feeding element to prevent the escape of short tobacco from between the combing element and the distributor and feeding elements.
